UNITED STATES PATENT OFFICE.

PHILIP WUEST, JR., OF PHILADELPHIA, PENNSYLVANIA, ASSIGNOR TO THE AUTO-MANUAL PIANO ACTION COMPANY, OF PHILADELPHIA, PENNSYLVANIA, A CORPORATION OF NEW JERSEY.

AUTOMATIC PLAYING MECHANISM FOR MUSICAL INSTRUMENTS.

No. 844,987.

Specification of Letters Patent.

Patented Feb. 19, 1907.

Application filed July 14, 1906. Serial No. 326,192.

To all whom it may concern:

Be it known that I, PHILIP WUEST, Jr., of Philadelphia, in the State of Pennsylvania, have invented certain new and useful Improvements in Automatic Playing Mechanism for Musical Instruments, whereof the following is a specification, reference being had to the accompanying drawings.

My invention relates to mechanism particularly adapted to play pianos, organs, and similar instruments, and of the kind comprising a series of pneumatic motors or strike-pneumatics respectively in operative relation to the individual sounding devices, and individual valve mechanisms controlled by a web of perforated paper, which is progressed with respect to a pneumatic tracker-bar provided with a series of apertures corresponding with a series of sounding devices.

Prior devices of this class are of two general types—first, instruments wherein all of the pneumatic-valve mechanisms and strike-pneumatics are mounted in a single chest common to all of them and consisting of a number of partition-boards grooved, fitted, and glued together to form valve-chambers and wind-ducts leading to and from the same; second, instruments wherein a plurality of substantially similar valve-casing sections or shelves are disposed in coöperative relation, each containing a divisional number of said valve mechanisms.

The first type of construction aforesaid is disadvantageous because all of the valve-chambers being rigidly related the contraction and expansion in different parts thereof causes accidental communication between the pneumatic ducts, which should be separate, and because to repair or remove any one valve it is necessary to manipulate the entire valve-chest.

The second type of construction above specified, although advantageous in that the adjustment or repair of any valve mechanism or strike-pneumatic is facilitated by limiting the number and extent of the parts which must be removed to afford access thereto, is more costly to manufacture than the first type aforesaid.

It is the object of my present invention to provide a structure which shall have the ad-

vantages of both types of prior construction aforesaid; and to this end I provide a single valve-casing or shelf containing all of the valve mechanisms arranged to control the entire series of strike-pneumatics and carrying a limited number of said strike-pneumatics, and employ with said single valve-chest separable shelves carrying divisional numbers of the strike-pneumatics alone.

It may be noted that the improved structure can be more economically manufactured than the devices of the prior art, for the reason that the valve-chambers, which are formed by boring operations, are localized in a single-board shelf or casing, as distinguished from the plurality of shelves or casings heretofore employed, which require separate manipulation for the boring operations.

My invention comprehends the various novel features of construction and arrangement hereinafter more definitely specified.

In the accompanying drawings, Figure I is a plan view of a structure conveniently embodying my improvements. Fig. II is an elevation of the front of said structure as shown in Fig. I. Fig. III is a vertical sectional view of said structure, taken on the line III-III in Figs. I and VIII. Fig. IV is a plan sectional view of said structure, taken on the line IV-IV in Figs. II and VIII. Fig. V is a plan sectional view of said structure, taken on the line V-V in Figs. II and VIII. Fig. VI is a plan sectional view of said structure, taken on the line VI-VI in Figs. II and VIII. Fig. VII is a plan sectional view of said structure, taken on the line VII-VII in Figs. II and VIII. Fig. VIII is a vertical sectional view of said structure, taken on the line VIII-VIII in Figs. I to VII, inclusive. Fig. IX is an elevation of the right-hand end of said structure as shown in Fig. II.

In said drawings, 1 is the single valve-casing or shelf, which is surmounted by the separable shelves 2 and 3, each supporting a divisional number of the set of strike-pneumatic bellows 4, arranged in such relation that their leaves 5 may be operatively engaged with the sounding devices of a musical instrument. Said casing 1 incloses the accum-chamber 6 and comprises the bottom

board 7, the removable top cover-board 8, and the removable front duct-board 9, which latter is also connected in removable relation with the shelves 2 and 3 aforesaid and carries the junction-bar 10 and guide-bar 11.

The flexible tubes 14 extend from respective apertures in a tracker-bar (not shown) through apertures in the guide-bar 11 and are connected to nipples 15 in the junction-bar 10, which register with ducts 16, extending through said bar, front duct-board, 9 and bottom board 7 and terminate in respective diaphragm-seats 18 in said bottom board 7 beneath the diaphragms 19. Each of said diaphragms 19 is in registry with a valve-chamber 20, inclosing a valve-plunger 21, carrying a vent-valve 22 and an exhaust-valve 23, the former controlling the opening 25, communicating with the atmosphere, and the latter controlling the opening 26 into the vacuum-chamber 6 in the casing 1, a partial vacuum being maintained in said chamber through the exhaust-conduits 28, during the operation of the instrument.

25 Referring to Fig. VIII, it may be observed that the valves 22 and 23 at the right-hand side of the chamber 6 control the strike-pneumatics, which are secured to the bottom of the casing 1, such control being effected 30 through the duct 30, which extends through the top cover-board 8 and bottom board 7. The valves 22 and 23 at the middle and left-hand side of said chamber 6 respectively control the strike-pneumatics supported by the 35 respective shelves 2 and 3 through the respective ducts 32 and 34, extending through the top cover-board 8, the front duct-board 9, and said respective shelves 2 and 3.

The form of my invention illustrated is arranged to coöperate with the sounding devices of a piano in which the inner ends of some of the digitals are diverged to avoid the supports for the action. Accordingly the strike-pneumatics are arranged in four groups 45 with sufficient space between them for said supports, each pneumatic being in registry with its respective sounding device.

As it is desirable that the ducts 32 and 34 shall be separated by walls of maximum thickness, they are spaced equally in the front duct-board 9, and offset recesses 33 and 35 are provided for connection with the unequally-spaced ducts in the respective shelves 2 and 3, as best shown in Figs. IV 55 and V.

Referring to Figs. VI and VII, it may be observed that the staggered relation of the valve-chambers 20 and the diaphragm-seats 18, which register therewith, permits the location of all of said valves 22 and 23 in a single board, which may be readily removed from the casing 1 when it is desired to repair or adjust said valves.

The structure including the casing 1 and shelves 2 and 3 is supported beneath the key-

board of a piano by brackets comprising knee-irons 40 and 41, which may be conveniently secured to said keyboard.

The knee-iron 40, which is adjacent to the free ends of the strike-pneumatics, is provided with apertures fitted to the screws 43, which secure the structure in rigid relation, so as to withstand the thrust of the strike-pneumatics; but the knee-iron 41, which is adjacent to the hinged ends of said strike-pneumatics, is provided with apertures 45, which are larger than the diameter of the screws 46 to permit the expansion and contraction of the boards due to atmospheric changes. It may be observed that by the last-described arrangement of their supports the strike-pneumatics 4 are always maintained in proper relation to the piano-action regardless of changes due to atmospheric conditions.

Referring to Figs. II, VIII, and IX, it may be observed that the ends 50 of the knee-irons 40 and 41 extend below the strike-pneumatics attached to the bottom of the casing 1, so as to support the entire structure and prevent accidental displacement of said pneumatics when said structure is removed from the piano-casing.

As shown in Fig. VIII, the strike-pneumatics 4 are conveniently secured by brads 52, inserted through apertures 53 in their respective movable leaves 5, said apertures being normally closed by the covers 55, of paper or other suitable material.

When any strike-pneumatic is brought into action (for instance, the lower one shown in section in Fig. VIII) as the result of a perforation in the web registering with its respective aperture in the tracker-bar, atmospheric pressure is admitted through the flexible tube 14 and duct 16 to the diaphragm-seat 18 and uplifts the diaphragm 19 and its corresponding valves 22 and 23, thereby closing the opening 25, leading to the atmosphere, and contemporaneously establishing communication between the vacuum-chamber 6 and the strike-pneumatic 4, through the opening 26 and duct 30, to collapse said strike-pneumatic, and thereby operate its respective sounding device.

In like manner the strike-pneumatics mounted on the shelves 2 and 3, above the chest 1, may be operated by their respective valves through the respective ducts 32 and 34.

I do not desire to limit myself to the precise details of construction and arrangement herein set forth, as it is obvious that various modifications may be made therein without departing from the essential features of my invention as defined in the appended claims.

I claim—

1. In an automatic playing device, the combination with a valve-casing; of strike-pneumatics mounted on the bottom of said casing; shelves above and distinct from said

- casing; strike-pneumatics mounted on said shelves; and, valves in said casing, arranged to respectively control all of said strike-pneumatics, substantially as set forth.
5. 2. In an automatic playing device, the combination with a valve-casing; of strike-pneumatics mounted on the bottom of said casing; shelves above and distinct from said casing; ducts connecting said shelves with said casing; strike-pneumatics mounted on said shelves; and, valves in said casing, arranged to control said strike-pneumatics through said ducts, substantially as set forth.
10. 3. In an automatic playing device, the combination with a valve-casing; of strike-pneumatics mounted on the bottom of said casing; shelves above and distinct from said casing; strike-pneumatics mounted on said shelves; valves in said casing, arranged to control said strike-pneumatics; and, pneumatics arranged to control said valves, substantially as set forth.
15. 4. In an automatic playing device, the combination with a valve-casing; of strike-pneumatics mounted on the bottom of said casing; shelves above and distinct from said casing; strike-pneumatics mounted on said shelves; valves in said casing, arranged to control said strike-pneumatics; and, pneumatics in said casing arranged to control said valves, substantially as set forth.
20. 5. In an automatic playing device, the combination with a valve-casing; of strike-pneumatics mounted on the bottom of said casing; shelves above and distinct from said casing; a duct-board connecting said casing with said shelves; strike-pneumatics mounted on said shelves; and, valves in said casing arranged to control said strike-pneumatics, substantially as set forth.
25. 6. In an automatic playing device, the combination with a valve-casing; of strike-pneumatics mounted on the bottom of said casing; shelves above and distinct from said casing; a duct-board forming a cover for said casing and a support for said shelves; strike-pneumatics mounted on said shelves; valves in said casing, arranged to control the strike-pneumatics on said shelves through respective ducts in said board, substantially as set forth.
30. 7. In an automatic playing device, the combination with a valve-casing; of strike-pneumatics mounted on the bottom of said casing; shelves above and distinct from said casing; strike-pneumatics mounted on said shelves; valves in said casing arranged to control said strike-pneumatics; and, brackets arranged to connect and support said casing and shelves, substantially as set forth.
35. 8. In an automatic playing device, the combination with a valve-casing; of strike-pneumatics mounted on the bottom of said casing; shelves above and distinct from said casing; strike-pneumatics mounted on said shelves; valves in said casing, arranged to control said strike-pneumatics, substantially as set forth.
40. 9. In an automatic playing device, the combination with a valve-casing; of a duct-board forming one cover of said casing; shelves distinct from said casing connected by said board; brackets rigidly connecting said shelves and said casing; and brackets loosely connecting said shelves and said casing in such relation as to permit the expansion and contraction of the parts, substantially as set forth.
45. 10. In an automatic playing device, the combination with a valve-casing; of a duct-board forming one cover of said casing; shelves distinct from said casing connected by said board; brackets securing said shelves and casing, having screw-apertures whose diameters are equal to the diameters of the securing-screws extending therethrough; and, brackets securing said shelves and casing having screw-apertures whose diameters are larger than the securing-screws extending therethrough, substantially as set forth.
50. 11. In an automatic playing device, the combination with a valve-casing; of strike-pneumatics mounted on the bottom of said casing; a duct-board; shelves above and distinct from said casing secured to said board; strike-pneumatics on said shelves arranged in definite relation to the respective sounding devices of the piano; and, valves in said casing arranged to control said strike-pneumatics, substantially as set forth.
55. 12. In an automatic playing device, the combination with a valve-casing; of valves in said casing; shelves distinct from said casing; strike-pneumatics on said shelves arranged in definite relation to the sounding devices of a piano; a duct-board connecting said casing and shelves, comprising ducts, equally spaced, leading from said valves to said strike-pneumatics; and, offset recesses in said ducts, substantially as set forth.
60. 13. In an automatic playing device, the combination with a valve-casing; of valves in said casing, arranged in staggered relation; shelves distinct from said casing; strike-pneumatics on said shelves arranged in definite relation to the sounding devices of a piano; a duct-board connecting said casing and shelves, comprising ducts, equally spaced, leading from said valves to said strike-pneumatics; and, offset recesses in said ducts, substantially as set forth.
65. 14. In an automatic playing device, the combination with a valve-casing; of strike-pneumatics mounted on the bottom of said casing; shelves above and distinct from said casing; strike-pneumatics mounted on said shelves; valves in said casing, arranged to

- control the strike-pneumatics on said shelves; pneumatics arranged to operate said valves; and, ducts arranged to connect said pneumatics with the atmosphere, substantially spaced; of shelves secured to said duct-board, having ducts arranged in groups and provided with offset recesses, arranged to register with the ducts in said duct-board; strike-pneumatics mounted on said shelves in registry with the ducts therein; and, valves in said casing arranged to control said strike-pneumatics, substantially as set forth. 5
15. In an automatic playing device, the combination with a valve-casing comprising a bottom board, and top cover-board; of strike-pneumatics mounted on the bottom of said casing; shelves above and distinct from said casing; a duct-board connecting said shelves and said casing; and, valves in said casing arranged to control said strike-pneumatics through ducts extending in the top cover-board, duct-board and respective shelves, substantially as set forth. 5
16. In an automatic playing device, the combination with a valve-casing comprising a bottom board and top cover-board; of strike-pneumatics mounted on the bottom of said casing; shelves above and distinct from said casing; a duct-board connecting said shelves and said casing; valves in said casing, arranged to control said strike-pneumatics through ducts extending in the top cover-board, duct-board and respective shelves; and, pneumatics in the bottom board, arranged to actuate said valves, substantially as set forth. 6
17. In an automatic playing device, the combination with a valve-casing comprising a bottom board and top cover-board; of strike-pneumatics mounted on the bottom of said casing; shelves above and distinct from said casing; a duct-board connecting said shelves and said casing; valves in said casing, arranged to control said strike-pneumatics through ducts extending in the top cover-board, duct-board and respective shelves; pneumatics in the bottom board, arranged to actuate said valves; and, ducts arranged to connect said pneumatics with the atmosphere, substantially as set forth. 7
18. In an automatic playing device, the combination with a valve-casing comprising a bottom board, top cover-board, and a front duct-board, having a series of ducts equally spaced; of shelves secured to said duct-board, having ducts arranged in groups and provided with offset recesses, arranged to register with the ducts in said duct-board; strike-pneumatics mounted on said shelves in registry with the ducts therein; valves in said casing arranged to control said strike-pneumatics and diaphragm-pneumatics arranged to control said valves, substantially as set forth. 8
19. In an automatic playing device, the combination with a valve-casing comprising a bottom board, top cover-board, and a front duct-board, having a series of ducts equally spaced; shelves secured to said duct-board, having ducts arranged in groups and provided with offset recesses, arranged to register with the ducts in said duct-board; strike-pneumatics mounted on said shelves in registry with the ducts therein; valves in said casing arranged to control said strike-pneumatics and diaphragm-pneumatics arranged to control said valves, substantially as set forth. 9
20. In an automatic playing device, the combination with a valve-casing comprising a bottom board, top cover-board, and front duct-board having a series of ducts equally spaced; shelves secured to said duct-board, having ducts arranged in groups and provided with offset recesses, arranged to register with the ducts in said duct-board; strike-pneumatics mounted on said shelves in registry with the ducts therein; valves in said casing, arranged to control said strike-pneumatics; diaphragm-pneumatics arranged to control said valves; ducts in said bottom board leading to said diaphragm-pneumatics; and, a junction-bar comprising ducts in registry with the ducts in said bottom board, substantially as set forth. 10

In testimony whereof I have hereunto signed my name, at Philadelphia, in the State of Pennsylvania, this 13th day of July, 1906.

PHILIP WUEST, JR.
